UNITED STATES PATENT OFFICE.

ROY CLIFFORD LEITCH, OF NEWTON, KANSAS, ASSIGNOR OF ONE-EIGHTH TO CHARLES D. BLACKMAN, OF DODGE CITY, KANSAS, AND ONE-EIGHTH TO WM. PETERS AND ONE-EIGHTH TO ADAM E. PURCELL, BOTH OF NEWTON, KANSAS.

GRAIN-CAR DOOR.

1,308,791.

Specification of Letters Patent.

Patented July 8, 1919.

Application filed December 14, 1917. Serial No. 207,136.

To all whom it may concern:

Be it known that I, ROY C. LEITCH, a citizen of the United States, and a resident of Newton, in the county of Harvey and State 5 of Kansas, have invented a new and useful Improvement in Grain-Car Doors, of which the following is a specification.

My present invention relates generally to car doors, more particularly to grain car 10 doors, my primary object being the provision of a simple, strong and durable construction conforming fully to the requirements of a door of this character, capable of effective manipulation for the usual purposes, and capable of ready movement to and 15 from operative position.

The above and various other objects of my present construction will be apparent from the following detailed description, referring 20 to the accompanying drawings, forming a part of this specification, and wherein:

Figure 1 is an elevation looking at the outside of a grain car equipped with my improvement.

Fig. 2 is an inside elevation with the door 25 in inoperative position.

Fig. 3 is a view partly in elevation and partly in vertical section, of a fragmentary portion of my improved door.

Fig. 4 is a detail section taken substantially on line 4—4 of Fig. 1.

Fig. 5 is a vertical transverse section taken substantially on line 5—5 of Fig. 1.

Fig. 6 is a detail vertical section taken on 35 line 6—6 of Fig. 5, and

Fig. 7 is a detail horizontal section taken on line 7—7 of Fig. 6.

Referring now to these figures, and particularly to Figs. 1, 2, 5, and 7, my improvements are utilized in connection with the 40 inner portion of the door opening 10 of a grain car 11, the frame of which includes door posts 12 at opposite sides of the opening, having vertically extending ribs 13 at 45 the inside of the car, one of which is particularly seen in Fig. 7, and also provided with apertures 14 in their opposing faces at opposite sides of the door opening 10 and intermediate the upper and lower ends thereof. The car frame also includes the usual 50 sill 15 which I provide with a flat sill plate 16 whose rear edge terminates substantially in the plane of the inner faces of the ribs 13, as well as a beam 17 extending across the

upper end of the door opening and known 55 as the door plate, the latter having supporting bearings 18 at its inner face for a horizontally disposed supporting rod 19, extending not only above the door opening at the inner side thereof, but having a portion 19^a, 60 as particularly seen in Fig. 2, which projects materially to one side of the door opening adjacent the upper portion of a frame 20 formed upon the inner surface of the car side at one side of its door opening for the 65 reception of my improved grain door in its inoperative position.

My improved grain door is adjustably supported by means of depending T-shaped hanger bars 21 which in the operative position of the door as seen in Fig. 1, are equidistantly spaced from one another and from the opposite sides of the door opening 10, or substantially so, the upper ends of these hanger bars 21 being rigidly secured to a 70 horizontally disposed hanger beam 22, the latter having at its opposite ends roller mounted brackets 23 engaging and shiftable upon the supporting rod 19 so that the door may be readily moved by the means stated, 75 from its operative position as seen in Fig. 1, to its inoperative position as seen in Fig. 2, and vice versa.

It will be noted by particular reference to Fig. 5, that the supporting rod 19 is so 85 spaced from the inner surface of the door plate 17, and the hanger beam 22 and bars 21 so proportioned and connected that when the door is in its operative position as shown in the figure mentioned, the upper ends of 90 these hanger bars 21 are disposed and held against the inner surface of the car plate and effectively braced by virtue of their contact therewith, for a purpose which will presently be made plain.

The main or body portion 24 of my improved grain door is preferably formed of a single piece of sheet material adapted to rest at its side edges against the inner surfaces of the ribs 13, and provided along its 95 said side edges with out-turned flanges 25 as best seen by reference to Fig. 7, at one side of the said ribs, and with vertically extending angle bars 26 secured therealong in spaced relation to the flanges 25 to engage the opposite or inner sides of the said ribs 13, said angle bars 26 having apertures 100 at certain points to register with the aper-

tures 14 of the ribs 13 before mentioned, when the door is in the operative position as seen in Fig. 1, for the reception of the upper angular ends of locking dogs 27 one of which is plainly seen in operative position, in full line in Fig. 6, each of these dogs having a V-shaped recess 28 in its upper end automatically engageable by the free end of a controlling lever 29. Each of the dogs 27 and its controlling lever 29 are respectively pivoted at 30 and 31 to the door 24, and have handles 32 and 33 by means of which they may be manipulated, it being observed that with its lever 29 depending 10 into engagement with the dog 27, as it does normally, movement of the said dog to the operative position shown in Fig. 6 will serve to elevate the free end of the respective lever 29 until the dog reaches its operative position, at which time the free end of the lever drops into the V-shaped recess so as to hold the dog in its operative position against any danger of accidental displacement due, for instance, to the vibration 20 of the car in connection with which my improvements are utilized.

In addition to the bracing effect the vertical flanges 25 and angle bars 26 have upon the body 24 of the door provided by my invention, the latter further has spaced pairs of parallel guide bars 34 which it will be noted, extend the full height of the door and are open to receive the hanger bars 21, the latter interfitting the spaces between the 30 guide bars 34 of each pair so that, considering the bearing the upper ends of the hanger bars 21 have against the door plate 17 in the operative position of the door, and the engagement of the lower portions 35 of these hanger bars within the guide bars 34 of the door 24, it is obvious that in operative position, rigid braces are thus provided vertically of the door in its operative position equi-distantly spaced from one another 40 and from the sides of the door opening so as to further enable the door to successfully resist the weight of the grain within the car.

The lower outer portions of the hanger 50 bars 21 projecting beyond the guide bars 34, as best seen in Fig. 4, have their inner opposing faces formed with longitudinal racks 35, and their outer opposite faces formed with a vertical series of ratchet 55 teeth 36, the latter engageable by means of dogs 37 as seen in Fig. 3, pivoted within brackets 38 upon the door beyond opposite sides of the pairs of guide bars 34, so that the door may be supported in elevated position with these dogs 37 in operative position, for instance at the height shown in the 60 inoperative position in Fig. 2 with the door shifted inside the car and to one side of the car opening and disposed within the 65 frame 20.

Each of the ratchet engaging dogs 37 has a handle 39 and may be held in the inoperative position shown in dotted lines at the right in Fig. 1, by means of a small lever 40, pivoted at 41 and provided at its opposite end with a handle 42, each lever having a limited movement in one direction against a stop 43, so as to hold the same in a position ready to drop beneath the handle portion of the respective dog 37 at all times, 70 should the latter be raised, in order to prevent full operative movement of the dog inwardly to engage its respective ratchet teeth 36.

Intermediate the upper and lower ends 80 of the door 24, a gear casing 44 is secured thereto transversely between the spaced pairs of guide bars 34, as best seen in Figs. 1, 3, and 4, the cover plate 45 of which gear casing has laterally spaced openings forming 85 bearings for the hub portions 46 of a pair of intermeshing gears 47 and 48, said hub portions being preferably provided with squared sockets 49 for the reception of a suitable tool, which by its application to 90 either gear obviously brings about rotation of both gears, due to their engagement.

The gears 47 and 48 are respectively in mesh with smaller gears 50 and 51, each of the latter in turn engaging the toothed 95 rack 35 of one of the hanger bars 21, so that upon rotation of either of the gear wheels 47 and 48, similar bearing is had upon the hanger bars 21 so as to either raise or lower the door in a truly vertical 100 direction and avoid undue friction upon those portions thereof in slidable engagement with the adjacent portions of the door frame.

The door 24 may have lower side vertically sliding trap doors 52 and 53 as seen in Fig. 1, and may also have handles 54 by which it may be shifted vertically when there is no pressure thereagainst. The door may also have a lower centrally disposed 105 and vertically shiftable latch member 55, manipulated from the inner face thereof and having a handle 56 as seen in Fig. 2, for engagement with a suitable keeper as seen in dotted lines in connection with the frame 110 20, so that the door may be latched within the said frame in inoperative position.

In addition to the vertical bracing of the door 24 as previously described, it is further braced by horizontally extending corrugated ribs 57 extending along its upper and lower edges and at an intermediate point, across its inner face, these ribs being hollow as best seen in Fig. 5, and the upper rib serving an additional function as a part 120 of the hinged connection of a vertically swinging door section 58. For this purpose, a rod 59 extends through the upper rib 57 and is engaged at its opposite outer end by the angular side arms 60 of the door sec- 125 130

tion 58 as best seen in Fig. 2, the rod 59 being journaled to move in the upper rib 57 so that the door section 58 may be swung to and from the operative position shown in Fig. 1, wherein it extends substantially in the vertical plane of the door 24. One face of the door section 58, which latter is braced by horizontal ribs 61, has a pair of pivoted catches 62 suitably spaced so that with the 10 door section in its upper operative position as shown in Fig. 1, these catches engage the inner portions of the hanger bars 21 to lock the door section 58 and prevent its accidental displacement to the lower inoperative position shown in Fig. 2, where it is folded against the inner face of the door 24.

In the operative position of the door, the upper hinged section 58 will not always be needed, but where it is in the operative position as shown in the figure mentioned, the catches 62 are released, and the door section 58 folded inwardly before the door 24 is shifted to inoperative position. The locking dogs 27 are then released and, with the 25 ratchet dogs 37 in operative engagement with the racks, a squared crank of any suitable nature is applied to one of the squared sockets 49, the gears being turned in that direction necessary to elevate the door 24 by virtue of engagement of the gears within the gear case, with the gear racks 35 of the hanger bars 21. When the door 24 has been elevated to the height shown in Fig. 2, the ratchet dogs 37 supporting the door in elevated position, the door is shifted laterally upon the supporting rod 19 by virtue of its movable engagement therewith, and previous to which the door is swung inwardly a slight distance, in order to clear the rib 13 at one side of the door, carrying the same into registering position with the frame 20 upon the inner face of the adjacent car side, into which the door is secured by the catch 55 so as to secure the door in inoperative position and in this way obviate danger of its injury while unsecured at the door opening.

In the operative position of the door 24, its lower edge abuts the inner edge of the sill plate 16 and thus in consideration of the 50 particular bracing of the door as previously described, it is obvious that my invention provides a strong, durable construction well calculated to withstand the heavy weight of grain within the car pressing outwardly 55 thereagainst in use, and one which may at

the same time be readily manipulated, as described.

I claim:

1. The combination with a door frame including an upper door plate, of a door engaging the inner face of the frame and having its body provided with spaced pairs of guide bars extending vertically along one face thereof, and suspension means for the said door including vertically projecting hanger bars, each of which has its lower end extending between the guide bars of one of the said pair of the guide bars of the door in the lowermost position of the latter, said hanger bars having their upper ends engaging the inner surface of the door plate in operative position, and said hanger bars and said guide bars being spaced from the sides of the door frame so as to coöperate with one another and form vertical braces for the door body in closed position.

2. The combination with a door frame including an upper door plate, of a grain door arranged to engage the inner sides of the frame and having pairs of vertically extending parallel guide bars forming guide channels between them, and extending substantially the full height of the door, and suspension means for the door including vertically disposed hanger bars, the upper ends of which engage the door plate when the door is closed and the lower ends of which extend into the guide channels formed by said guide bars when the door is in lowermost position, said guide bars and said hanger bars being equi-distantly spaced from one another and from the sides of the frame.

3. A grain car door having vertically extending guide channels, vertical hanger bars the lower portions of which extend into the said guide channels and have opposing rack faces, a gear casing carried by the door and extending between the said hanger bars, and gears within the casing in engagement with one another and with both of the said guide bar racks, certain of said gears having tool engaging means and being located adjacent relatively opposite sides of the gear casing, for the purpose described.

ROY CLIFFORD LEITCH.
